US0D1066647S

(12) **United States Design Patent** (10) **Patent No.:** **US D1,066,647 S**
(45) **Date of Patent:** **** Mar. 11, 2025**

(54) **MASK**

(71) Applicant: **Se Mi Im**, Yongin-si (KR)

(72) Inventor: **Se Mi Im**, Yongin-si (KR)

(**) Term: **15 Years**

(21) Appl. No.: **29/795,584**

(22) Filed: **Jun. 18, 2021**

(30) **Foreign Application Priority Data**

Jun. 3, 2021 (KR) 30-2021-0026461

(51) **LOC (15) Cl.** **29-02**

(52) **U.S. Cl.**

USPC **D24/110.1**

(58) **Field of Classification Search**

(57) **CLAIM**

The ornamental design for a mask, as shown and described.

DESCRIPTION

FIG. 1 is a front side perspective view of a mask showing my new design;

FIG. 2 is a rear side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate portions of the mask that form no part of the claimed design.

1 Claim, 7 Drawing Sheets
